MEANS FOR THREADING PAPER THROUGH
BLUEPRINT MACHINESHarold J. Brunk, Chicago, Ill., assignor to The
C. F. Pease Company, a corporation of DelawareOriginal application May 4, 1940, Serial No.
333,415. Divided and this application July 30,
1943, Serial No. 496,737

4 Claims. (Cl. 34—120)

This invention relates to improvements in blueprint machines, and particularly to means for threading the paper through the same.

The object of the invention is to provide improved means for threading a span of blueprint paper and similar sensitized sheets through the drying section of a continuous drying machine which means are particularly well adapted for use in a machine in which the drying drums are rotated by mechanical driving means, as contrasted with rotation by the frictional contact therewith of the traveling span of paper pulled through the machine from the rear end. This application is a division of my application 333,415, filed May 4, 1940; High speed blueprinting machines, and patented October 19, 1943; No. 2,332,296.

The accompanying drawings illustrate a commercial embodiment of the invention.

Fig. 1 is a side elevation of the drying section of the machine;

Fig. 2 is a partly diagrammatic side elevation of the complete machine;

Fig. 3 is a front elevation of the first heating drum and part of the driving mechanism therefor;

Fig. 4 is a side elevation thereof;

Fig. 5 is a front elevation of the threading device; and

Fig. 6 is an end elevation thereof, on a larger scale.

In Fig. 1 the sheet of sensitized paper, which in this case is blueprint paper, is indicated in its travel through the machine by reference 10 and is unwound from a supply roll (not shown) mounted at the front of the machine, which latter is indicated as a whole by reference 11. The sheet of paper is drawn past a source of light (Fig. 2) such as a series of arc lamps 12, in the usual manner, and passes over or around a number of rolls as it moves to the rear of the machine and then forwardly and upwardly to the heating drums over which it travels from front to rear.

The heating drums 60, as shown in Figs. 1 and 2, are arranged preferably in two horizontal rows at the top of the rear portion of the machine, the upper row comprising in this instance five heating drums whereas the lower row comprises four heating drums, although the number may be varied to meet different requirements. The rolls are mounted in staggered relation so that the paper 10 passes substantially half way around each heating drum and up and down in

substantially vertical spans to the rear of the machine.

The foremost heating drum 60, shown in Figs. 3 and 4, has trunnions or bearing hubs 61 and 62 by means of which it is mounted in the side frames 63 and 64, roller bearings 65 being preferably provided. The sprocket 66, by which said drum is rotated, is mounted on the outside of the frame with another sprocket 67 mounted between it and said frame. The chain drive for the sprocket 66 is hereinafter described. On the inside of the same frames, above the journals, are mounted a pair of smaller idler sprockets 68, 68. As shown in Fig. 3, the plane of said sprockets is positioned between the plane of the main driving sprocket 66 and the adjacent end of the heating drum 60.

As shown in Fig. 1, the paper 10, after leaving the heating drums 60, passes downwardly around an idler 70 to a driven roll 71 and thence to a loose roll of paper 72 which rests in and is rotated by a pair of driven belts 73, 74 arranged in V-shaped formation in a conventional manner. The roll 71 rotates at a rate which will provide a surface speed a little in excess of the speed of travel of the paper, as hereinafter described, so as to tend to maintain the paper under tension. In order to hold the paper in closer frictional contact with said roll, several belts 75, 75 are provided which are mounted on rolls 76, 77 with one of their spans in each case in frictional engagement with the paper. The roll 77 is an idler roll but the roll 76 is positively driven, and at a rate which will insure a surface speed of the belt a little in excess of the speed of the travel of the paper. Any suitable mechanical connections may be employed for driving said roll 76, as for example, a spur gear on its shaft meshing with another spur gear on the shaft of the roll 71, shown in Fig. 2. Thus the paper is engaged on both sides by moving surfaces which tend to maintain it under the desired tension.

As hereinafter described, in the embodiment 45 of the invention shown herein, each drum is positively driven by a chain and sprocket connection and hence reliance is not placed on a wind-up roll at the end to pull the paper around the drums.

The means for rotating the drying drums will now be described. A motor 80 (see Fig. 2) is mounted in the base of the machine, and, through an enclosed reduction gearing, drives a chain 81 which in turn drives a pinion 82 near one end 55 of a shaft 83; a pinion 84 near the other end

of which drives a chain 85. This chain drives the first heating drum in the series, through the sprocket 66 previously identified in Figs. 3 and 4. The adjacent sprocket 67, on the same axis of rotation, drives a chain 86 which, as shown in Fig. 2, passes down and up alternately over similar sprockets 87, one of which is mounted at the corresponding end of each of the remaining drums. Said driving chain returns in a horizontal span under idler sprockets 88, 89, as shown in Fig. 2.

As shown also in Fig. 2, the chain drive from the motor also drives an additional chain 90, with its spans arranged substantially horizontally and extending to the rear of the machine where it drives a vertical chain 91 through suitable sprockets, which chain drives an additional chain 92 which rotates the roller 50 mounted in the potash tank 42, shown also in Fig. 1. The chain 91 also drives a further chain 93 which rotates the roll 71 at a surface speed somewhat in excess of that of the paper, as previously stated.

The threading device constituting the basis of this divisional application is shown in more detail in Figs. 3, 4, 5 and 6, and may assume the form of an attachment, although in this case it is built as part of the machine. It comprises a pair of threading chains 100, 100, one of which is mounted near one end of the various heating drums and the other is mounted at the other end, as shown in Fig. 3, so that said chains are spaced apart a distance slightly greater than the length of said drums. These chains pass over the idler sprockets 68, 68, which are arranged in pairs, as shown in Figs. 2 and 4. As shown in Fig. 2, the sprockets 68 which are adjacent the upper row of heating drums, are disposed above the bearing hubs of the drums, while those sprockets adjacent the lower row of heating drums are disposed below the respective bearing hubs. Thus it will be seen that the sprockets are eccentrically mounted with respect to the bearing hubs of the associated drums as contrasted with a concentric mounting which would require a special bearing hub construction, and a more costly sprocket construction. The provision of a pair of sprockets eccentrically mounted with respect to each of the bearing hubs causes the chains to follow a path which coincides more or less with the path followed by the paper in passing around the heating drums, as will be evident by a comparison of Figs. 1 and 2. These idler sprockets are supported on suitable stub shafts 101, mounted adjustably in the adjacent portions of the side frames of the machine. The lower span of each threading chain passes over additional sprockets 102 and 103, (Fig. 2), on each side, one pair of which is mounted on a shaft provided with a crank 104 whereby the sprockets 103 may be rotated by hand, to cause said chains to travel in the same direction as the normal travel of the paper.

As shown in Figs. 5 and 6, each chain is provided at one point in its length with an elongated cotter pin 105 with a short link 106 rotatably mounted thereon. The free ends of said links support opposite ends of a cross bar 107 surrounded by a length of aluminum tubing 108.

If the paper breaks during the operation of the machine, the attendant stops said machine. The end of the main sheet, which may be assumed to have passed over one or more but not all of the heating drums at the time the breakage occurred, is then wrapped around or otherwise fastened to the cross bar, i. e., to its aluminum

housing, and the machine started. At the same time the operator rotates the sprockets 103 by turning the crank 104, and thus causes the cross bar to follow an up and down and rearward path almost paralleling the path traversed by the paper. During this hand feeding period, the operator maintains a slight pressure on the paper so as to avoid any slack due to the tendency of the heating drums to feed the paper forwardly, and after the broken end of the paper reaches the rear of the machine it is quickly disconnected from the cross bar, rolled up by hand and placed on the V-shaped supports afforded by the belts 73 and 74, after which the machine continues to operate in the usual manner.

The links 106, which pivotally support the cross bar, permit the latter to deviate slightly from the exact path pursued by the threading chains 100. Thus this arrangement compensates for the discrepancy arising from the slight difference in the path of travel of said chains, which pass around two small sprockets near the end of each heating drum along a path which projects beyond the periphery of each drum, as compared with the travel of the paper along a circular path, of a radius represented by the radius of each heating drum.

Since these threading chains are normally at rest, the idler sprockets on which they are mounted are not subjected to any wear during the normal operation of the machine and as they are mounted on bearings of much less diameter than the bearings of the heating rolls, they are not only subjected to less friction but may be much smaller than would otherwise be the case and hence may be formed economically by a stamping process.

Changes in the construction and arrangement may be made without departing from the spirit and scope of the invention as disclosed in the appended claims.

I claim:

1. The combination with a drying machine comprising a frame, drying drums rotatably mounted therein, and means for driving said drums to draw the sheet to be dried through the machine, said means comprising a sprocket fixed to one of the bearing hubs of each drum, a chain passing over said sprockets to rotate said drums, of a threading device comprising a pair of thin idler gears mounted in said frame eccentrically with respect to each of said bearing hubs, a second set of idler gears similarly mounted near the other end of each drum, chains passing over said idler gears, a link pivoted to each of said chains, a cross bar connecting said links and means for advancing said chains and cross bar to thread the paper around said drying drums.

2. In a drying machine comprising a frame, drying drums rotatably mounted thereon in two horizontal rows arranged at different levels, means for driving all of said drums at substantially the same speed to draw the material to be dried up and down and around said drums, a plurality of idler sprockets mounted near each end of said drums, an endless chain mounted on the sprockets at one end of said drums, and a second endless chain mounted on the sprockets at the other end thereof, to follow substantially the path of said material but spaced therefrom, an attachment on each chain movable with respect thereto, a cross-bar secured at opposite ends to said movable attachments, and means to advance said two chains at the same speed and independently of the speed of said drums where-

by said material may be threaded through said drums.

3. The combination with a drying machine comprising a frame, drying drums rotatably mounted therein, and means for driving said drums to draw the sheet to be dried through the machine, said means comprising a sprocket fixed to one of the bearing hubs of each drum on the outside of said frame, a chain passing over said sprockets to rotate said drums, of a threading device comprising idler gears mounted on the inside of said frame eccentrically with respect to each of said bearing hubs, a second set of idler gears similarly mounted near the other end of each drum, chains passing over said idler gears, a link pivoted to each of said chains, a cross bar connecting said links and means for advancing said chains and cross bar to thread the paper around said drying drums.

4. The combination with a web processing machine having a frame and a plurality of drums with bearing hubs journaled in said frame, of a threading device comprising two sets of gears, 5 each set being mounted on said frame at the opposite ends of said drums, a plurality of gears of each set being provided adjacent each of said bearing hubs and being eccentrically disposed with respect thereto, a pair of chains each passing over one set of said gears, a link pivoted to each of said chains, a cross bar connecting said links and adapted to engage the leading end of a web to be processed, and means for advancing said chains and cross bar to thread the web 10 around said drums.
